[57] CLAIM

The ornamental design for a combined holder for a memo pad and food store coupons, as shown and described.

DESCRIPTION

FIG. 1 is a top, left front perspective view of a combined holder for a memo pad and food store coupons showing my new design;

FIG. 2 is a front elevational view;

FIG. 3 is a top plan view;

FIG. 4 is a right side elevational view;

FIG. 5 is a left side elevational view;

FIG. 6 is a rear elevational view; and,

FIG. 7 is a bottom plan view thereof.

FIGS. 2 through 7 have been drawn to a reduced scale with respect to FIG. 1.

FIG. 1

FIG. 2

FIG. 3

FIG. 4

FIG. 5

FIG. 6

FIG. 7
